UNITED STATES PATENT OFFICE.

THOMAS V. CROMWELL, OF ST. LOUIS, MISSOURI.

WIRE WALL-POCKET.

942,714.

Specification of Letters Patent.

Patented Dec. 7, 1909.

Application filed March 10, 1909. Serial No. 482,460.

To all whom it may concern:

Be it known that I, THOMAS V. CROMWELL, a citizen of the United States, residing at St. Louis, in the State of Missouri, 5 have invented new and useful Improvements in Wire Wall-Pockets, of which the following is a specification.

This invention relates to wall pockets, the object of the invention being to provide a 10 simple, practical and cheaply manufactured wall pocket of wire fabric especially designed for advertising purposes and so constructed as to enable a large number of such pockets to be compactly nested together.

15 To the above end the invention consists in the construction, combination and arrangement of parts herein fully described, illustrated and claimed.

In the accompanying drawings: Figure 1 20 is a perspective view of a wall pocket embodying the present invention. Fig. 2 is a detail vertical cross section through a portion of the front wall of the pocket. Fig. 3 is a detail horizontal section through the same.

25 In the manufacture of the improved wall pocket, a single length of wire is bent into proper shape to form an arched marginal top wire 1 with a central supporting eye or loop 2, integral side bars 3 forming the 30 margins of the back of the pocket, forwardly extending bottom wires 4 forming the ends of the bottom of the pocket, upstanding marginal wires 5 defining the opposite side edges of the front wall of the pocket, and a

35 connecting wire 6 forming the top marginal wire of the top wall of the pocket. All of the marginal wires thus far described are formed in one piece from a single length of wire of the requisite gage to give the necessary 40 stiffness to the wall pocket as a whole. The end frames are each formed from a single length of wire and separately from each other, the wire being bent into a continuous section of a triangle to comprise the 45 downwardly converging side bars 7 and 8, the top connecting wire 9, the bottom connecting wire 10, the top wire 9 being of greater length than the bottom wire 10.

The end frames or sections are covered with 50 meshed wire fabric as shown at 11 and the back, bottom and front walls of the pocket

are also covered with corresponding meshed wire fabric as shown at 12, 13 and 14 respectively, the marginal wires forming side bars of the front, back and bottom of the 55 pocket and the corresponding bars of the separately formed end walls being lashed or wired together in any convenient manner.

Secured to the outer side of the inclined front wall of the pocket is a plate or panel 15 which may be of any desired size to contain advertising or other matter. This plate or panel is secured permanently to the front wall of the pocket by means of hanger straps 16 of metal which are folded centrally 60 around adjacent horizontal wires of the fabric, as shown in Fig. 2, said straps being folded upon themselves and brought to lie against the inner face of the plate 15 against which they are securely held and clenched 70 by means of split rivets 17 inserted through perforations in the plate 15 and the straps 16 and clenched behind the straps as shown in Fig. 3, each of the rivets being provided with an enlarged head 18 which lies against 75 the outer exposed surface of the plate or panel 15. The extremities of the straps are retained between the rear side of the plate 15 and one or more of the horizontal fabric wires of the front wall of the pocket as 80 shown in Fig. 2.

I claim:

A wire wall pocket embodying a back, a bottom, an inclined front, and end walls, all composed of wire fabric and reinforcing 85 marginal frames, in combination with a plate or panel secured to the front wall of the pocket, hanger straps of metal embracing the fabric wires of the front wall, and split rivets inserted through said plate and 90 through the hanger straps, each of said straps being folded upon itself and having the extremities thereof held between said plate and one or more of the fabric wires of the front wall of the pocket, substantially 95 as described.

In testimony whereof I affix my signature in presence of two witnesses.

THOMAS V. CROMWELL.
